UNITED STATES PATENT OFFICE.

SAUL BERMANN, OF NEW YORK, N. Y.

RADIATOR.

1,184,160.

Specification of Letters Patent. Patented May 23, 1916.

Application filed February 18, 1915. Serial No. 8,993.

To all whom it may concern:

Be it known that I, SAUL BERMANN, a subject of the Czar of Russia, residing at New York city, New York, have invented 5 certain new and useful Improvements in Radiators, of which the following is a specification.

My invention relates to improvements in radiators, particularly for automobiles, and 10 has especial reference to the construction and arrangement of the supporting ribs or fins for the radiator tubes.

As is well known in the art, the radiator tubes require cooling to provide for the 15 radiation of enough thermal units to keep the water in the tubes from changing into vapor form. At the present time, air cooling of these tubes is most generally resorted to, and my invention is especially concerned with air cooled radiators.

It is of course eminently desirable that all the tubes of a radiator shall be subject to uniform cooling action of the air but it has been found, in practice, that with the present 25 construction of supporting ribs or grids, the end tubes are more vigorously cooled than the intermediate tubes.

The principal object of my invention is to provide a construction of radiator in which 30 all the tubes will be subjected to adequate air-cooling.

A further object of the invention is to provide a form of ribs or supporting grid which need not be connected with the radiator 35 tubes, although forming an effective support therefor. The individual ribs of the grid are preferably provided or formed with means to prevent damaging the tubes by contact of the ribs therewith, and with 40 means for connecting the ribs together.

The invention will be clearly understood from the following description thereof, in connection with the accompanying drawing, wherein—

45 Figure 1 is a front elevational view of an automobile radiator constructed according to my invention; Fig. 2 is a horizontal sectional view thereof on the line 2—2 of Fig. 1; Fig. 3 is an elevational view of a number of ribs assembled to form a grid; Fig. 50 4 is a plan view of Fig. 3; Fig. 5 is a similar view of a formed up rib; Fig. 6 is a cross sectional view on the line 6—6 of Fig. 5; and Fig. 7 is a plan view of a blank from which 55 the ribs are formed up.

Referring to the several figures of the

drawing by reference characters, 10 denotes the water tank of the radiator, the parts of which are interconnected by the upright radiator tubes 11. To support the tubes 11 in position, and provide for regulating the flow of air thereto, I place adjacent these tubes one or more grids, which are built up of superimposed units or ribs, preferably constructed of blanks such as shown 65 in Fig. 7. The blank, which is of rhomboidal form, includes a plane body portion 12, longitudinal lateral flanges 13, and ears 14 at opposite ends of each flange. Traversing the body portion 12 diagonally is a slot 70 15, which extends substantially the length of the blank.

To shape the blank for the purpose of forming the same into a rib of the desired shape, the flanges 13 with their integral ears 75 14 are bent along the lines 16, at substantially right angles to the plane of the body portion 12. This operation results in producing a rib such as that shown in plan in Fig. 5, and in cross section in Fig. 6.

The supporting grid is formed by superimposing any desired number of such ribs in vertical alinement, and suitably connecting, as by means of solder or otherwise, the ears 14 of one rib with the next higher succeeding rib. If desired, the ribs may be additionally interconnected and reinforced by the rods or wires 17 engaging in grooves formed in one end edge of the ribs. A grid 85 of this kind, or a number of such grids, 90 may be placed between adjacent series of tubes 11 (Fig. 2) the upturned flanges 13 resting against the tubes. These flanges are smooth, and are thus not likely to injure the tubes as a result of the vibration to 95 which a vehicle radiator is normally subjected.

In connection with the grids above described, I prefer to employ means for regulating the flow of air to the tubes 11. The 100 preferred means comprise deflector plates 18 inserted through the slots 15 in the ribs 12. Each plate 18 is approximately as wide as the slot 15 is long, and may be made sufficiently high to extend through the series 105 of ribs forming one or more grids. These plates are obliquely placed, (the slots 15 being oblique) and so guide the air which passes between the tubes that the intermediate tubes will be as well cooled as the 110 end tubes. It will be understood that ordinarily a fan is carried by the vehicle near

the inner side of the radiator, such fan cooling the inner radiator tubes, while the in-rushing air is relied upon to cool the outer and intermediate tubes.

- 5 As above stated, it was found in practice that the intermediate tubes were not adequately cooled by the air flowing past the same, and my improved construction obviates this defect by deflecting the air from its 10 normal straight path between the tubes, and causing it to follow a path inclined from one side or end of the tubes to the other. In this way the intermediate tubes are as well cooled as the tubes at either side or end of 15 the radiator.

What I claim as new and desire to secure by Letters Patent is:—

1. A radiator construction for the purpose specified, comprising radiator tubes, 20 and a supporting grid therefor consisting of a series of superimposed ribs each there-

of being provided with a slot extending substantially from end to end of the rib and inclined toward the radiator tubes, and a deflector plate extending through the slots in 25 the ribs.

2. A radiator construction for the purpose specified, comprising radiator tubes, a supporting grid therefor consisting of a series of superimposed ribs each of which 30 includes a body portion having a longitudinal slot therein inclined toward said radiator tubes, and also having lateral flanges and ears projecting from said flanges, and a deflector plate inserted through the in- 35 clinied slots in said ribs.

In testimony whereof I have affixed my signature in presence of two witnesses.

SAUL BERMANN.
